UNITED STATES PATENT OFFICE.

MAURICE F. FITZGERALD AND PATRICK J. FITZGERALD, OF TORRINGTON,
CONNECTICUT.

SIGNAL-HORN.

1,125,083.

Specification of Letters Patent. Patented Jan. 19, 1915.

Application filed October 29, 1913. Serial No. 798,077.

To all whom it may concern:

Be it known that we, MAURICE F. FITZGERALD and PATRICK J. FITZGERALD, citizens of the United States, residing at Torrington, in the county of Litchfield and State of Connecticut, have invented certain new and useful Improvements in Signal-Horns; and we do declare the following to be a full, clear, and exact description of the invention, 10 such as will enable others skilled in the art to which it appertains to make and use the same, reference being had to the accompanying drawings, and to the letters and figures of reference marked thereon, which form 15 a part of this specification.

This invention relates to signals for automobiles and other vehicles, but more particularly to a horn having a diaphragm arranged and adapted to be vibrated by a 20 motor for the purpose of giving forth a warning signal which is audible for a great distance and which is clear in tone and not displeasing to the ear.

With this object in view the invention 25 consists in the novel construction of the striker mechanism for vibrating the horn diaphragm; and the invention consists in certain novel features of construction and in certain novel instrumentalities for producing an unbroken series of hammer blows 30 upon the diaphragm.

In the usual construction of mechanism for vibrating diaphragms of this character 35 certain cam constructions are employed which in operation have a wiping action on the diaphragm which is not conducive to the proper vibration of the same. We have found by careful experimenting in this art that the proper blow upon the diaphragm 40 in order to produce the best and most efficient vibrating of the same is a direct hammer blow struck parallel with the axis of the diaphragm. Such a blow upon the diaphragm when given in rapid succession produces a vibration of the diaphragm which 45 causes the same to emit a clear resonant sound superior in quality to the sound emitted from the diaphragm when the same is given a wiping blow as is usual in this 50 class of instruments.

Referring to the accompanying drawing: Figure 1 is an elevation partly in section of a signal horn constructed in accordance with this invention. Fig. 2 is a rear plan view of 55 the vibrating diaphragm. Fig. 3 is a front

elevation of the striker mechanism, the diaphragm and bell or horn being removed. Fig. 4 is a fragmentary view of the striker mechanism illustrating the same in its normal position shown in dotted lines and also 60 illustrating the same in its operative position shown in full lines, and Fig. 5 is a diagrammatic edge elevation of the diaphragm illustrating the striker mechanism in full and dotted lines, the purpose of this view 65 being to show the hammer action of the striker mechanism.

Like numerals of reference indicate the same parts throughout the several figures in which:

1 indicates the device which comprises the bell or horn 2, motor 3, vibrating diaphragm 4 and striker mechanism 5, it being of course understood that any suitable motor either electric, manually operated or other 75 type can be employed in connection with this invention without in any way departing therefrom, as we lay no claim in this application to any specific motor for driving the 80 striker mechanism.

Referring now to the vibrating diaphragm 4 it will be seen that the same is suitably secured at its periphery at 6 in order to rigidly hold the same in proper position in relation to the striker mechanism 5, and it will be seen that a series of projections 7 are arranged on the face of the diaphragm for engagement by the striker mechanism 5.

Referring to Fig. 1 with particular relation to Fig. 4 it will be seen that upon the shaft 8 of the motor we arrange a resilient member 9, said resilient member being preferably a piece of flat spring metal so secured to the shaft 8 by means of a nut 10 as to rotate with the shaft.

Upon the resilient member 9 and near the ends thereof we provide a rounded projection 11 and upon the opposite side of the resilient member 9 and at each end thereof we provide a counterpoise 12.

Having thus described the several parts of this invention its operation is as follows: The striker mechanism 5 being arranged in relation to the vibrating diaphragm, in the manner as shown in Fig. 1, the two projecting members 11 of the striker mechanism are barely in engagement with the projections 7 on the vibrating diaphragm 4. Upon rotation of the striker mechanism 5 the counterpoise on each end of the resilient 105

member 9 is carried by centrifugal force into position shown in full lines in Fig. 4. This movement of each counterpoise 12 causes the resilient member 9 to assume the 5 position shown in full lines in Fig. 4, which, as will be clearly apparent from an inspection of the accompanying drawing, causes the two projecting elements 11 on the resilient member 9 to be brought in line of strong 10 contact with the projections 7 on the vibrating diaphragm 4. As soon as one of the projections 7 on the diaphragm 4 is engaged by one of the projections 11 on the resilient member 9 of the striker mechanism the projections 7 thus engaged throw the projection 11 of the resilient element 9 away from the diaphragm and instantly the centrifugal force acting on the counterpoise 12 throws 15 the projection 11 on the striker mechanism into engagement with the next or succeeding projection 7 on the vibrating diaphragm 4 exactly in the manner as is illustrated diagrammatically in Fig. 5. Thus it will be seen that upon proper rotation of the striker 20 mechanism each of the projections 7 on the vibrating diaphragm 4 is given a direct hammer blow by the projecting elements 11 of the striker mechanism in such manner that a proper vibration is imparted to the 25 vibrating diaphragm to cause the same to emit a clear penetrating and resonant sound.

A further advantage derived from this construction is that practically no sound is emitted from the horn until the motor has 30 reached a sufficient speed to cause the striker mechanism to be brought into strong contact with the diaphragm by means of centrifugal force; consequently the motor is allowed to attain a high number of revolu-

tions before the striker mechanism engages the projections on the diaphragm to effect a strong vibration thereof.

Having thus fully described the invention what we claim as new and desire to secure by Letters Patent is:—

1. In a device of the character described, a diaphragm, a series of projections thereon, a rotatable striker mechanism located in close relation to said diaphragm, said striker mechanism including a flexible member, projections mounted thereon in line of slight contact with the projections on said diaphragm, and weighted elements on said striker mechanism to flex said flexible element and to move said projections thereon by centrifugal force into strong contact with said projections on said diaphragm upon rotation of said striker mechanism.

2. In a device of the character described a diaphragm, a series of projections thereon, a rotatable striker mechanism located in close relation to said diaphragm, said striker mechanism including flexibly mounted means rotatable therewith to engage said projections on said diaphragm and including means free to move under the influence of centrifugal force and rotatable with said striker mechanism to move said flexibly mounted means of said striker mechanism into strong contact with said projections on said diaphragm.

In testimony whereof, we affix our signatures, in presence of two witnesses.

MAURICE F. FITZGERALD.
PATRICK J. FITZGERALD.
